SASH BALANCE

Filed Oct. 19, 1931

INVENTOR:-
ALBERT H. KERSTING.
By Martin D. Smith, ATTY.

UNITED STATES PATENT OFFICE

ALBERT H. KERSTING, OF LOS ANGELES, CALIFORNIA

SASH BALANCE

Application filed October 19, 1931. Serial No. 569,575.

My invention relates to a sash balance of the type wherein the tension of a spiral spring is utilized for counterbalancing the weight of the sash with which the balance is associated and the principal objects of my invention are, to generally improve upon and simplify the construction of the existing forms of spring sash balances, to provide simple and efficient means for producing and maintaining a certain degree of frictional resistance between the drum on which the sash supporting cable winds and the housing of the sash balance and further, to provide simple and efficient means whereby the degree of frictional resistance thus produced may be adjusted for window sash of varying weights.

A further object of my invention is, to provide a sash balance of the character referred to, wherein the inner convolutions of the spiral spring are utilized in connection with other parts for producing the desired frictional engagement between the cable carrying drum and the housing of the sash balance.

With the foregoing and other objects in view, my invention consists in certain novel features of construction and arrangement of parts that will hereinafter be more fully described and claimed and illustrated in the accompanying drawing in which:

Fig. 1 is a front elevational view of a sash balance constructed in accordance with my invention and with a portion of the front plate broken away.

Fig. 2 is a vertical section taken approximately on the line 2-2 of Fig. 1.

Fig. 3 is an enlarged horizontal section taken approximately on the line 3-3 of Fig. 1.

Fig. 4 is a horizontal section similar to Fig. 3 and showing a modified form of the sash balance.

Fig. 5 is a detail section showing the connection between the outer end of the spiral spring and the peripheral wall of the drum on which the cable winds.

Fig. 6 is an elevational view looking in the direction indicated by the arrow 6 in Fig. 4.

Fig. 7 is a detail section showing the connection between the inner end of the spiral spring and the tubular shaft or axle that supports said spring.

Fig. 8 is a perspective view of the tubular shaft or axle that serves as a support for the spiral spring in the species disclosed in Figs. 1, 2 and 3.

Referring by numerals to the accompanying drawing which illustrates a practical embodiment of my invention, 10 designates the housing of the balance which is substantially rectangular in form and stamped or pressed from suitable sheet metal.

A front wall of cover plate 11 of sheet metal serves as a closure for the housing 10 and by means of screws or like fastening devices 12, the ends of the cover plate are secured to the housing 10 and to the stile S of the window frame.

Arranged in the upper and lower portions of the housing are horizontally disposed tubular members 13 that serve as supports or fixed axles for the spiral springs and for the drums that enclose said spiral springs and the rear end of each of these tubular members 13 is provided with two or more rearwardly projecting ears 14 that extend through arcuate apertures that are formed in the rear wall of housing 10 and the outer ends of said ears are riveted down against the outer face of the rear wall of the housing so as to rigidly secure the tubular member to said housing.

Formed integral with the front end of the tubular member 13, is a forwardly projecting ear 15 that extends through an aperture that is formed in the cover plate 11 and after the parts of the balance have been properly assembled within the housing, the outer end of this ear 15 is riveted down against the outer face of the cover plate as hereinafter more fully described.

The length of the tubular member 13 is such that its forward end terminates a short distance inwardly from the inner face of the cover plate 11.

Formed in the tubular member 13 is a longitudinally disposed slot 16, through which passes a hook 17, that is formed on

the inner end of a spiral spring 18 and the outer end of this spring is detachably secured in any suitable manner, preferably by means of a hook 19 to the peripheral portion 5 of a cable carrying drum.

This drum comprises a disc-like wall 20, provided at its center with an opening for the accommodation of the tubular axle 13 and formed around said opening is a narrow flange 21 that bears on the tubular member 13.

The central portion of the wall 20 is dished so that only the outer portion of said wall bears against the wall of housing 10 15 and formed integral with the edge of the wall 20 of the drum is a peripheral wall 22 that is inclined or flared so that it gradually increases in diameter away from the wall 20.

A flange 23 is formed between the outer 20 edge of wall 20 and the adjacent edge of the peripheral wall 22 and the opposite edge of said peripheral wall 22 terminates in an outwardly projecting flange 24.

A flexible member 25, preferably a metal 25 cable, is secured to and is adapted to wind upon the inclined peripheral wall 22 of the drum and the free end of this cable carries a hook 26 or like device that is connected to the window sash.

30 A bow spring 27 is arranged between the spring 18 and the rear wall 20 of the drum, the ends of which spring bear on the face of the wall 20 opposite the face that is in contact with the wall of housing 10 and 35 formed in the center of this spring 27 is an aperture 28 for the accommodation of tubular member 13.

When properly positioned between the rear wall 20 of the drum and spring 18, the 40 intermediate portion of spring 27 engages the rear edges of the inner convolutions of said spring 18.

When the parts of the sash balance have 45 been properly assembled and with the ear 15 on the forward end of tubular member 13 projecting through the front wall 11, the projecting end of said ear is riveted down so that the portion of the cover plate 11 adjacent to the forward end of tubular member 50 13 and the ear 15 bears directly against the front edges of the inner convolutions of the spring 18 and, as this particular portion of wall 11 is forced inwardly during the riveting operation, the engaged inner convolutions 55 of spring 18 will press the central portion of spring 27 toward the rear wall of the drum, thereby increasing the tension in spring 27, so that its ends will bear with considerable pressure against the rear wall 60 20 of the drum and consequently cause said rear wall to bear with considerable friction against the wall of housing 10.

Before being placed in service, the sash balance is tested by connecting the end of 65 the cable to a suitable tension gauge and

unreeling said cable and the operator or workman that assembles the sash balance produces the desired degree of friction between the cable carrying drum and the housing by regulating the amount or degree of 70 riveting that is imparted to the ear 15.

In the modified construction illustrated in Fig. 4, the spring 27 and the ear 15 on the forward end of tube 13 are dispensed with and a screw 29 is inserted through an aperture in plate 11^a and said screw passes axially through the tubular hub or axle 13^a that supports the spiral spring 18^a. The threaded end of this screw is seated in the rear wall of housing 10^a and as said screw is 80 tightened, the portion of the front wall 11^a, adjacent to the head of the screw bears against the front edges of the innermost convolutions of the spring 18^a and acts through said convolutions to press the central portion of the rear wall of drum 20^a rearwardly and thereby increase the tension between the outer portion of said rear wall 20^a and the real wall 10^a of the housing. 85

Thus it will be seen that I have provided 90 a sash balance having a spiral spring for counterbalancing the weight of the sash with which the balance is associated and said balance being provided with simple and efficient means whereby the inner convolutions 95 of the spiral spring are utilized for producing and maintaining the desired degree of frictional resistance between the spring and closing drum and the housing of the balance.

It will be understood that minor changes 100 in the size, form and construction of the various parts of my improved sash balance may be made and substituted for those herein shown and described without departing from the spirit of my invention, the scope 105 of which is set forth in the appended claims.

I claim as my invention:

1. In a sash balance, a housing, a tubular axle secured to one of the walls of the housing a cable carrying drum arranged for rotation upon said axle, a spiral spring arranged within said drum, the inner end of which spring is connected to said axle, the outer end of which spring is connected to the peripheral portion of said drum and means 115 for causing the inner convolutions of said spring to exert constant pressure against said drum.

2. In a sash balance, a housing, a tubular axle secured to one of the walls of the housing, a cable carrying drum arranged for rotation upon said axle, a spiral spring arranged within said drum, the inner end of which spring is connected to said axle, the outer end of which spring is connected to the 120 peripheral portion of said drum and means including the inner convolutions of said spring for forcing said drum into frictional engagement with one of the walls of said housing. 125

3. In a sash balance, a housing, an axle arranged within said housing and secured to one of the walls thereof, a cable carrying drum mounted for rotation on said axle, a spiral spring within said drum, the outer end of which spring is secured to the peripheral portion of said drum, the inner end of which spring is secured to said axle and a bow spring arranged between said spiral spring and the wall of said drum.

4. In a sash balance, a housing, an axle arranged within said housing and secured to one of the walls thereof, a cable carrying drum mounted for rotation on said axle, a spiral spring within said drum, the outer end of which spring is secured to the peripheral portion of said drum, the inner end of which spring is secured to said axle, a bow spring arranged between said spiral spring and the wall of said drum and means for causing the inner convolutions of the spiral spring to engage with pressure against the central portion of said bow spring.

5. In a sash balance, a housing, an axle arranged within said housing and secured to one of the walls thereof, a cable carrying drum mounted for rotation on said axle, a spiral spring within said drum, the outer end of which spring is secured to the peripheral portion of said drum, the inner end of which spring is secured to said axle and means for drawing those portions of the walls of the housing adjacent to the ends of the axle toward each other and causing the innermost convolutions of the spring to exert pressure against said drum.

6. In a spring sash balance, a housing, a cable carrying drum arranged for rotation within said housing and frictionally engaging one of the walls thereof, a spiral spring arranged within said housing and adapted to yieldingly resist rotary motion of said drum in one direction and means cooperating with the walls of said housing and acting through the inner convolutions of said spiral spring for imparting pressure to that portion of the drum that frictionally engages the wall of said housing.

7. In a spring sash balance, a housing, a drum mounted for rotation within said housing, a spiral spring arranged within said drum and adapted to yieldingly resist rotary motion thereof in one direction and adjustable means including the inner convolutions of said coil spring for exerting pressure on the wall of the drum and causing same to frictionally engage the wall of said housing.

In testimony whereof, I affix my signature.
